BUILDING CONSTRUCTION

Frederick M. Venzie, Philadelphia, Pa.

Application December 13, 1930. Serial No. 502,156

7 Claims. (Cl. 72—118)

This invention, generally stated, relates to a building construction and has more particular relation to floor slabs as utilized in connection with a building construction.

5 One object of the present invention is to provide a floor construction in which the floor slabs of cementitious material have interlocked relation one with another, considered both laterally and longitudinally of the flooring as a whole.

10 A further object of the present invention is to provide a floor structure of the character stated in which each floor slab along its longitudinal edge is arranged to have interlocked relation with a companion slab by means of a knuckle-like connection of parts.

15 A further object of the present invention is to provide a floor structure of the character stated in which each slab is provided with longitudinal means for interlocking with a companion slab through a hook and eye connection.

20 A further object of the present invention is to provide a floor construction of the character stated in which means is provided whereby in the case of fire or excessive heat the beams employed in connection with the channels are prevented from canting.

25 A further object of the present invention is to provide a structure of the character stated in which longitudinal plasterer's channels are employed between adjacent floor slabs, which plasterer's channels are relatively retained in proper position through the instrumentality of hook-like members co-adjacent with the interlocking mediums as employed in each floor slab.

30 A still further object of the present invention is to provide a floor structure of the character stated in which the plasterer's channels and the hook and eye connections are reinforced by means of laterally extended cross wires.

35 A still further object of the present invention is to provide a construction of the character stated in which unskilled mechanics may expeditiously assemble a flooring, and a still further object of the present invention is to provide a structure of the character stated which is simple in construction, relatively cheap to manufacture, and the individual slabs of which may be manufactured at a central plant and shipped to the point of erection, ready for assembly.

40 Other and further objects of the present invention reside in the provision of general details of construction and in the arrangement, combination, and connection of parts for attaining the results sought by the foregoing objects.

45 The invention consists of the novel construc-

tion hereinafter described and finally claimed.

The nature, characteristic features and scope of the invention will be more fully understood from the following description taken in connection with the accompanying drawings forming 60 part hereof, and in which:

Fig. 1 is a more or less diagrammatic view in plan of a series of floor slabs assembled in accordance with the present invention;

Fig. 2 is a view in side elevation of that slab 65 shown at the left hand side of Fig. 1, and looking toward the left in said Fig. 1;

Fig. 3 is a similar view of the same slab but viewed in the opposite direction;

Fig. 4 is a view in longitudinal section taken 70 upon the line 4—4 of Fig. 1;

Fig. 5 is a view in cross section of assembled floor tiles embodying the invention;

Fig. 6 is a view in longitudinal section taken 75 upon the line 6—6 of Fig. 1;

Fig. 7 is a view in end elevation of one of the slabs shown in Fig. 1;

Fig. 8 is a similar view of the same slab viewed from the opposite end;

Fig. 9 is a view in cross section taken upon the 80 line 9—9 of Fig. 1;

Fig. 10 is a view in perspective of one of the hook-like members shown in Fig. 1; and

Fig. 11 is a view in perspective of one of the 85 wire clips shown in Fig. 4.

For the purpose of illustrating my invention I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

Referring to the drawings in detail, the reference numeral 10 designates an elongated floor slab of cementitious material and in practice a series of these slabs are positioned upon the 90 tops of floor beams, usually I-beams, which are illustrated in the accompanying drawings. Each floor slab 10 longitudinally considered is provided with a series of fingers 11, between adjacent fingers there being provided spaces 12. The fingers 11 project outwardly upon each side of a slab 10 in a plane above the base of a slab but projected beyond the boundary of the slab base line. Embedded in and extended through each 100 of the slabs horizontally, in spaced relation, are

110

rods 13, usually of wire, each having at one end a hook 14 and at its opposed end an upturned portion forming a pin 15. In practice the hooks 14 of a slab are fitted over a pin 15 of an adjacent slab to provide a continuous interlock of slabs throughout the length of a building structure. Also, in practice the knuckle-like arrangement of fingers 11 and slots 12 of adjacent slabs are fitted together to form an interlock of slabs laterally considered throughout a building structure. Thus, in laying a floor it is not necessary to accurately space the floor beams because the interlock of slabs both longitudinally and laterally considered tends to maintain the slabs efficiently sustained even though a floor beam is not immediately beneath adjacent ends of floor slabs. The reference numeral 16 designates plasterer's channels, one of which is arranged between adjacent floor slabs longitudinally considered from end to end of a building structure. These channels also serve to provide a continuous interlock of slabs. Each channel iron rests upon the opposed meeting flanges 17 of the floor slabs as best seen in Fig. 9. These channel irons 16 tie together by means of a wire coupling 8 bent substantially U-shaped fashion and having the respective ends bent over as at 19 to engage over the tops of the channel irons and the bottoms of the wire couplings 18 being extended below the hooks 14 of the rods 13, see Fig. 9. Each finger 11 has depending therefrom a pin 20 which is the terminus of a cross coupling 21 of wire, best seen in Fig. 7. In positioning the plasterer's channels 16 the same are arranged so as to rest upon the flanges 17 and the slabs 10 and to be engaged by these pins 20. In order to prevent canting of the floor beams 33 in case of fire or severe heat, I provide hook members, best seen in Fig. 11, which members are provided at their upper ends with a hook-like portion 23 and at their lower portions with a horizontally arranged part 24. In practice the hook-like part 23 is introduced over a plasterer's channel 16 and the lower end of the device is positioned beneath the upper flange of the floor beam 22, as best seen in Fig. 4 of the drawings, it being understood that the vertical portion 25 of each of these hook-like devices passes through apertures in the floor slab. At least one end of each floor slab 10, as best seen in Fig. 7, is provided with a hand grip 26 whereby the mechanic may suitably tilt a floor slab to cause engagement of the hook and eye connections previously described. It is to be observed that the coupling 21 is up-turned as at 27 in opposed relation to the pendant pins 20 and that the terminus of each part 27 is flush with the top of a floor slab 10 in order to facilitate ready transportation of a floor slab. In the connection it is to be noted that the pendant pins 20 and the upwardly extended portions 27 of the couplings 21 cooperate to form plasterer's channels retaining mediums. In practice with the floor slabs 10 in assembled position the knuckle-like joint connections are filled in with cementitious material not shown in the drawings, whereby the interlock of parts is completed. By the above arrangement and construction of parts an interlock both longitudinally and laterally considered is provided throughout the entire length of a building structure. The slabs may be assembled expeditiously by unskilled labor to provide an interlock of slabs efficiently, thus doing away with either accurately spacing floor beams or manufacturing floor slabs of such dimensions as

to accurately span floor beams, as it at present practiced in plasterer's trade.

The slabs when arranged in end to end position have interlocked relation by reason of the hooks and eyes throughout the entire building structure, and the reinforcement as found in each slab makes for a continuous interconnected reinforce throughout the length of a building structure. Also, the interlock of the slabs laterally considered makes for a continuous, reinforced, cross arrangement of flooring.

What is claimed is:

1. In a building structure of the character stated, rectangular floor slabs of pre-cast cementitious material the opposed longitudinal edges of each slab being provided with spaced, laterally disposed fingers, the fingers of adjacent slabs being arranged to have interlocked connection one with another, and the lateral edges of which have interlocked, hook and eye connection one with another. 90 95

2. In a building structure of the character stated, rectangular floor slabs of pre-cast cementitious material the opposed longitudinal edges of each slab being provided with spaced, laterally disposed fingers, the fingers of adjacent slabs being arranged to have interlocked connection one with another, a channel iron arranged between adjacent longitudinal edges of said slabs, and laterally disposed mediums for connecting said channel irons in parallelism. 100 105

3. In a building structure of the character stated, rectangular floor slabs of pre-cast cementitious material the longitudinal edges of each slab being provided with spaced, laterally disposed fingers, the fingers of adjacent slabs being arranged to have interlocked connection one with another, a channel iron arranged between adjacent longitudinal edges of said slabs, laterally disposed mediums for connecting said channel irons in parallelism, metallic floor members for supporting said slabs, and means including metal-clips for connecting said channel irons and floor members to prevent canting under excess heat. 110 115 120

4. In a building structure of the character stated, rectangular floor slabs of pre-cast cementitious material the longitudinal edges of each slab being provided with spaced, laterally disposed fingers, the fingers of adjacent slabs being arranged to have interlocked connection with one another, the lateral edges of which have interlocked hook and eye connection one with another, a channel iron arranged between adjacent interlocked longitudinal edges of said slabs, and means arranged laterally of said slabs for tying said channels together. 125 130 135

5. In a building structure of the character stated, rectangular floor slabs of pre-cast cementitious material the longitudinal edges of each slab being provided with spaced, laterally disposed fingers, the fingers of adjacent slabs being arranged to have interlocked connection one with another, the lateral edges of which have interlocked, hook and eye connection one with another, a channel iron arranged between adjacent interlocked longitudinal edges of said slabs, and means arranged laterally of said slabs for tying said channels together, said means engaging over said channel irons and beneath said hook and eye connection. 140 145

6. In a building structure of the character stated, rectangular floor slabs of pre-cast cementitious material the longitudinal edges of each slab being provided with spaced, laterally 150

disposed fingers, the fingers of adjacent slabs being arranged to have interlocked connection one with another, and the lateral edges of which have interlocked, hook and eye connection one with another, a channel iron arranged between adjacent interlocked, longitudinal edges of said slabs, and means arranged laterally of said slabs for tying said channels together, said means including a substantially U-shaped coupling engaging over said channel irons and beneath said hook and eye connection.

7. In a building structure of the character stated, rectangular floor slabs of pre-cast cementitious material the longitudinal edges of

each slab being provided with spaced, laterally disposed fingers, the fingers of adjacent slabs being arranged to have interlocked connection one with another, the lateral edges of which have interlocked, hook and eye connection one with another, a channel iron arranged between adjacent interlocked edges of said slabs, means arranged laterally of said slabs for tying said channels together, I-beams for supporting said floor slabs, and substantially L-shaped clips for engaging over said channel irons and the upper flange of the I-beams to prevent canting of the I-beams under excess heat.
